UNITED STATES PATENT OFFICE.

JULIUS A. RAABE, OF ST. LOUIS, MISSOURI.

TOY.

SPECIFICATION forming part of Letters Patent No. 425,343, dated April 8, 1890.

Application filed May 21, 1889. Serial No. 311,621. (No model.)

To all whom it may concern:

Be it known that I, JULIUS A. RAABE, of the city of St. Louis, in the State of Missouri, have invented a certain new and useful Improvement in Toys, of which the following is a full, clear, and exact description, reference being had to the accompanying drawings, forming part of this specification, and in which—

10 This toy has a cup set transversely at the end of a stem and a ball secured thereto by an elastic connection.

Figure I is a perspective view of the toy. Fig. II is a perspective view showing a modification of the cup. Fig. III is a detail enlarged side view.

The cup 1 may be made of any suitable material. In Fig. I the material is sheet metal with orifices giving lightness and improved 20 appearance. In Figs. II and III the cup is shown as formed of wire. The stem or staff 2 I prefer to form of thin sheet-metal tubing, but do not confine myself to any special material or detail of construction. The stem 25 and handle 3 may suitably be made of wood. Between the stem and the cup is a flexible connection 4, which is shown as consisting of a coil of wire, but which may be made of rubber. This flexible connection is for the pur-

pose of increasing the difficulty of catching 30 the ball and thus make the toy more interesting and amusing in use, for it will be understood that the position of the cup or basket 1 will be rendered uncertain. The ball 5 may preferably be made of light wood, papier- 35 maché, or rubber, either hollow or solid. The cord 6 between the ball and the cup I prefer to make of elastic material, such as rubber, but inelastic material may be used, such as common string or thread. I prefer to secure 40 one end of the cord 6 to the bottom of the cup, as seen in Figs. II and III; but the cord 6 may be attached to another part of the cup or to the stem or flexible connection 4.

7 is a whistle in the end of the handle 3. 45

I claim as my invention—

1. The combination of the cup 1, stem 2, flexible connection 4 between the stem and cup, and ball 5, connected to other part of the toy by cord 6, substantially as set forth. 50

2. The combination of the stem 2 with cup 1, secured thereto by a flexible connection 4 between the stem and cup, the ball 5, and elastic cord 6, connecting the ball to the cup.

JULIUS A. RAABE.
